[57] CLAIM

The ornamental design for a scalpel, as shown and described.

DESCRIPTION

FIG. 1 is a side elevational view of a scalpel showing my new design, the opposite side elevational view being a mirror image;

FIG. 2 is a top plan view;

FIG. 3 is a bottom plan view thereof;

FIG. 4 is a cross-sectional view, taken along the line 4—4 in FIG. 2;

FIG. 5 is a front elevational view thereof;

FIG. 6 is a rear elevational view thereof;

FIG. 7 is a cross-sectional view taken along the line 7—7 in FIG. 1; and,

FIG. 8 is a cross-sectional view taken along the line 8—8 in FIG. 1.
